UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

TYPEWRITING MACHINE.

Application filed July 7, 1922. Serial No. 573,316.

To all whom it may concern:

Be it known that I, JOHN A. WHERRY, a citizen of the United States, residing in New Orleans, in the parish of Orleans and 5 State of Louisiana, have invented certain new and useful Improvements in Typewriting Machines, of which the following is a specification.

The present invention relates to the art 10 of so-called continuous billing in typewriting machines; that is to say, to the typing of entries on sheets fed through the machine in a continuous chain, as, for instance, for the issuance to many individuals of 15 statements or notices, alike as to form.

Heretofore a single continuous sheet or web, having the forms repeated thereon, or several of such webs, superposed for interleavement with carbons, have been fed, 20 from supply rolls or packages, to the platen, thereafter to have the individual forms cut therefrom. An object of the present invention is the provision of means whereby, as the work progresses, the forms may be 25 separately inserted into the machine and there linked with the preceding forms for the feed thereof through the machine; thus relieving the machine and its carriage of 30 any mechanism involved in feeding and guiding a continuous form-web from a roll, or the like, to the platen.

Bills and other forms are commonly provided with a detachable stub on which is duplicated a portion of the entry; such stubs 35 being used as receipts or kept by the maker. An object of the invention is the provision of means whereby individual forms having such stubs may be fed in a chain through the machine, and whereby the duplicate 40 entry on the stub may be made simultaneously with its original on the other part of the form; thus saving the time and trouble of making the same entry in different column-positions of the platen and of 45 moving the carriage from one such position to another.

In connection with the foregoing, a feature of the invention is the provision of a carbon-belt on which the individual forms 50 are placed, one after the other, the form being folded around the same; so that the carbon while serving as the carrier, also effects the duplication on the stub.

An object of the invention is a shaping or cutting of the individual forms at one edge 55 thereof, such that, when the edge of a form, being positioned on the belt, is set against the opposing edge of the preceding form, it will be held or guarded by that preceding form for passage as a link in the form-chain through the machine. As hereinafter shown, by cutting the forms on the line of the stub-fold, and more particularly, by making the stub of less height than the body 60 of the form, the leading edge of one form folded on the belt may be brought down behind the upper opposing edge of the body of the preceding folded form, until arrested in such guarded position by the upper edge 65 of the stub of the preceding form. 70

A feature of the invention is the provision of means engageable by the bights of the folded forms as the same are slipped over the belt, for aligning the side margins of 75 the forms, and for maintaining such alignment, as to each form, until by movement of the belt the form is gripped on the platen.

A further feature of the invention is the provision of means for successively discharging the typed forms from the belt. 80 In the preferred form of the invention, such discharging means consists of a stationary finger, projecting into the path of the bights of the forms, and so directed or shaped as to cam the forms off of the belt; or at least 85 to cause the forms to move laterally outward on the belt until the weight of the stubbed ends thereof cause the same successively to fall from the belt.

An object of the invention is the provision of means whereby individual forms may be fed downward and around the platen from the front thereof, and the writings thereon be duplicated in condensed form on a talley-sheet fed in the opposite direction; 95 and more particularly, of means whereby such feed of the forms may be effected by movement of the platen independently of a line-space mechanism which is operable, on each carriage-return, to effect a feed of the 100 talley-sheet independently of the platen.

A feature of the invention is the provision of means whereby a plurality of superposed carbon-belts may be used, so that any desired number of duplicates may be made of 105 the entries on the individual forms; and so

that, by inserting two of the belts in superposed position between the folds of the forms, the entries on the stub may be in a different color than those on the body of the form. Another feature of the invention is the provision of means for easy insertion of the form-stub between two superposed belts, to eliminate, at will, one of the belts as a printing medium; and of means for changing the setting of a belt between effective and ineffective positions.

Commonly, in this art, the desired entry is made on a single line; and thus the speed with which the work can be turned out depends largely upon the movements involved in feeding the forms successively to the printing line, and in thereafter discharging the same from the machine. From the foregoing description, it will be seen that the number of manual operations involved in continuous billing according to the present invention, is reduced to a minimum. Except for the placement of the forms on the carbon, there is no manual movement of the carbons with respect to the forms. There is no cutting of the leading typed form from those which follow it: the discharge of the typed forms is automatic. No shift of the platen or of the feeding devices, to release the forms from the carbons or tally-sheet, is required after one form is typed and before another form is in printing position. The feed of the tally-sheet is automatic. The feed of the forms is a front feed, thus further便利ening the operator. No shift of the carriage from one to another column-position, for writing on the stub, is involved. All is conducive to speed and ease of operation.

Other features and advantages will hereinafter appear.

In the accompanying drawings,

Figure 1 is a view, in front elevation, of the assembled apparatus on the carriage of a typewriting machine.

Figure 2 is a view, in side elevation, taken on the line 2—2 of Figure 1.

Figure 3 is a top plan view of the rear of the continuous carbon-carrier-frame and certain associated parts.

Figure 4 is a view, in side elevation, showing the drive of the upper carbon-carrier-roll from the platen.

Figure 5 is a view of one of the bill-forms with stub-extension, laid out flat.

Figure 6 is a view, in perspective, of the form shown in Figure 5; the stub being shown as folded.

Figure 7 is a view, in side elevation, showing the manner in which the succeeding stubs are interlocked for guidance around the platen.

Figure 8 is a view, in cross-section, on the line 8—8 of Figure 2, showing the manner in

which the bill-forms and carbons are supported with respect to each other in the machine above the printing line.

A platen 10 is fast to a shaft 11, journaled in the end plates 12 of the platen-frame. Also fast on the shaft 11 is a hand-wheel 13,

by means of which the platen may be turned in feeding the individual work-pieces to the printing position. The machine is also equipped with line-space mechanism. In

using the machine for the purposes of the present invention, however, the line-space mechanism is disconnected from the platen and is only employed, as will hereinafter be noted, for effecting a line-space-feed of the tally-sheet. The line-space mechanism here

employed is that shown and described in detail in United States Patent, to Helmond, No. 1,150,366, dated August 17, 1915, to which reference is made for an understanding thereof in detail.

Briefly, it comprises a line-space-wheel 14, revolvably mounted on the platen-axle 11 and actuatable by means of a pawl 15 on a slide 16, carried by the left-hand frame-piece 12. The slide 16 is moved

backward by the carriage-return-lever, as in the standard Underwood typewriting machine, to cause the pawl 15 to turn the line-space-wheel 14, and is returned to normal position by a spring (not shown).

Fast to the line-space-wheel 14 is a drum 18, acting as one element of a clutch, the other element of which, not shown, is contained within the drum 18 and is fast to the axle 11.

When the two clutch-members are locked together, the line-space-wheel will turn the platen. For locking and unlocking the clutch-members, there is provided a tapered

stud or cam piece 19, shiftable longitudinally on the platen-axle, by means of pins 20, carrying a finger-piece 21. Movement of

the finger-piece 21 to the right locks the line-space-wheel 14 to the platen-axle. In setting the machine for the present invention, however, the finger-piece 21 is moved to the left, to the position shown in Figure 1, in

which the platen is free of the line-space mechanism.

For supporting the carbon-pulleys and certain other features of the present invention, there is a frame comprising side plates

26. A shaft 22, mounted in the end plates 12 of the platen-frame, passes through, and supports, the plates 26. Set-screws passing

through bosses 23 on the plates 26 serve to fix the plates on the shaft 22. The plates 26, in addition to being supported on the shaft 22, which is a fixed shaft, are also pro-

vided at their lower ends with rollers 27, by means of which they ride and are, in part, supported by the platen. Each of the plates or brackets 26 has, at its upper end, an ear

28, offset thereon and provided with a pin 29. When the brackets 26 have been fixed

in place upon the shaft 22, they are sprung toward each other, to permit a cross-tie or bar 30 to be locked thereto, by means of bayonet-joint connections which slots 31 in the bar 30 form with the pins 29. Upon release of the brackets 26, they spring to their normal setting, causing the bar to be securely held thereby. The bar 30 thus serves as a cross-brace for a frame of which the brackets 26 form a part.

The frame which immediately carries the carbon-pulleys is supported by the brackets 26. This latter frame comprises a pair of uprights 32, secured by screws 33 at their lower ends to the brackets 26. Near their upper ends, the uprights 32 are connected and braced by a bar 34, having ears 35, secured by rivets or screws 36 to the uprights. Above the bar 34, the uprights are extended and have journeled therein a shaft 37, to which a pulley 38 is made fast, by means of a set-screw 39. The frame, of which the uprights 32 are elements, also comprises bars 40, secured to the uprights 32 by the rivets 36 and extending therefrom rearward, one on each side of the frame. In the rear ends of the bars 40 is journaled a shaft 41, to which is made fast another pulley 42. Secured to each of the bars 40, intermediate the ends thereof, by means of rivets 43, is a downward and forward extending arm 44. The arms 44, at their lower ends, carry a plate 45 (see Figures 2 and 3). In Figure 3, the right-hand arm 44 is shown as having an offset, to provide for an extension of the plate 45 at that side. As shown in Figure 2, the upper forward edge of the plate 45 is curled at 46, to engage and rest upon the upper beaded edge 47 of the usual paper-shelf 48. The paper-shelf 48, being supported on the platen-carriage, serves as a support for the pulley-frame on the platen-carriage to the rear of the support thereon provided by the brackets 26.

In Figure 2, two endless carbon sheets or belts 49 and 50 are shown as led over and downward from pulley 38, to and around the platen between the latter and the apron and paper-shelf 48, to and around the rear pulley 42, and thence upward and forward to the pulley 38. The usual front and rear pressure-feed-rolls 51 and 52 are indicated in the drawings. As shown in Figure 1, however, these rolls are beyond the edges of the carbon-belts, and, consequently, the latter, in passing around the platen, are not engaged by the feed-rolls. In order, however, that the carbons may snugly embrace the platen, so as to be fed around by and with the latter when the platen is turned by the hand-wheel 13, the carbon-belts are held taut. For holding the belts 49 and 50 taut, idlers 53 and 54, respectively, are provided. The idler 53 is journaled in the ends of arms 55, loosely pivoted on the shaft 37

of the upper pulley. The weight of the idler 53 and arms 55 eliminates slack in the belt 49. Similarly, the idler 54 is journaled in the ends of arms 56, loosely pivoted on the pulley-shaft 37. Collars 57, held by set-screws 58 to the shaft 37, hold the arms 55 and 56, and assist in holding the pulley 38, against longitudinal displacement on the shaft 37, and provide for longitudinal adjustment of these parts on the shaft 37. A collar 59, held to the shaft 37 by a set-screw 60, holds the shaft 37 against such longitudinal displacement as might cause it to become disconnected from the frame-members 32. To assist in the feed of the carbon-belts, and in order that there may be no undue pull or strain thereon, by the platen, such as might tend to tear the same, a drive is provided from the platen to the pulley 38. This drive consists of a coil-spring belt 61, set in an annular groove 62 in the end of the platen and in a grooved pulley, made fast by a screw 64 to the pulley-shaft 37. The effective diameters of the pulley 63 and of the groove 62 in the platen are the same, and the diameters of the pulley 38 and of the platen are the same, so that the pulley 38 is driven at the same peripheral speed as the platen as and when the latter is turned by the hand-wheel 13.

As shown in Figure 2, the outside belt 49, in passing from the pulley 38 to the platen, passes along the outside face of a plate 65, secured to and supported by the bar 30 on the brackets 26. The purpose of this plate 65 is to provide a smooth surface, between which and the outside carbon-belt the folded stub 66 of the individual bill-forms may be inserted in positioning the bills on the endless carbon-belts. Otherwise trouble or delay might be experienced in positioning the bill-forms, particularly where the bill-form-stubs are to be inserted between two carbon-belts. The length of the plate from top to bottom is shown as somewhat greater than the length of the bill-form; and the plate extends down to a point near the platen. The upper and lower edges of the plate are preferably curled, as indicated at 67, so that the carbon-belts will not catch upon the same.

Two carbon-belts are shown so that the writing on the duplicate forms, that is to say, on the folded stub of the individual bill-forms, may be either black or red. Ordinarily, the belt 49 for printing on the individual bill-stubs will be a black belt; in which event the belt 50 would be a red belt. When it is desired to print the duplicates or stubs in black ink, the red belt is led, as shown in Figure 2, from the pulley 38 back of the plate 65 and is available, if desired, for such use, to print upon the tally. For guiding the red belt back of the plate 65,

the latter on its rear face is provided with ears 68, carrying upper and lower idle pulleys 69, over which the red belt passes, and by means of which the red belt is held spaced 5 away from the plate 65. Where the red belt is to be used for printing on the bill-stubs, it is passed down with the black belt in front of the plate 65. The plate 65 is readily removable to permit it to be placed 10 behind both belts, or, as shown in Figure 2, to be placed between the two belts.

The manner in which the individual bill-forms are inserted and carried through the machine is as follows. With the belt positioned as shown in Figure 2, and the individual forms having previously been folded on the dotted line 70 (see Figure 5), the individual folded forms are passed in front of the plate 65, laterally from the right-20 hand side, in such manner that the stub 66 thereof enters between the belt 49 and the plate. For aligning the folded right-hand margin of the combined bill and stub, and for determining the position to which the 25 same is moved over the plate in the operation of inserting the same, there is provided a flat, thin gage-finger 71, which is held by screws 71^a at its upper end to the cross-tie 34, and which depends therefrom, 30 in front of the plate 65, to its distal end 71^b, below the lower edge of the plate 65. The gage-piece 71 is spaced forward of the plate 65 sufficiently to permit the folded stub 66 of the bill-form to be passed between 35 the same and the plate 65. As shown in Figure 1, the gage-piece 71 is clear of the carbon-belt at the right-hand side of the latter. In inserting the bill-form, therefore, the stub 66 passes first behind the 40 gage-piece 71 and then behind the belt, and the body-portion of the bill-form passes to the outside of both the gage-piece and the belt. When the folded bill-form has been moved until the bight thereof comes into 45 engagement with the right-hand edge of the gage-piece, it is properly aligned and positioned for forward feed with the belt.

Thus positioned, the folded bill-form, or rather the leading one of such forms, is 50 slid downward along the aligning member 71 until the bottom edge thereof may be engaged by the front pressure-rolls 51, and thereupon be fed with the belt and by rotation of the hand-wheel 13 to printing position. It will be noted that the length of 55 the gage-piece 71 is sufficient to hold the folded bill-form properly aligned until the same can be engaged by the feed-rolls.

As shown in Figure 5, the stub-portion 60 of the individual form is cut away on a line 72, below the upper edge 73 of the main portion 74 of the form. A quarter of an inch thus cut from the top of the stub will ordinarily be sufficient for the purposes intended. The purpose of this cut, as shown

in Figure 7, is to permit the lower edge 75 of a succeeding form to be inserted behind the upper edge 73 of the preceding form. Since, in inserting the form, the same is folded around the aligning piece 71, the 70 succeeding form inserted, as indicated, behind the upper edge of the preceding form, must come to rest and be stopped with its lower edge 75 on the upper edge 72 of the stub of the preceding form. The cutting 75 away of the stubs on the lines 72, therefore, not only allows for an overlapping of the succeeding form by the preceding form, but provides a positive means for determining the amount of overlap and the proper relative position of the forms along the carbon-belt for feed through the machine. A succeeding form thus overlapped by a preceding form cannot spring out and foul any 80 of the printing instrumentalities or guides 85 in passing through the machine.

With only the black belt 49 in front of the plate 65, the printing on both the main portion 74 and on the stub-portion 66 of the form, both original and duplicate, will 90 be in black. When printing in red on the duplicate or stub 66 is desired, and both belts 49 and 50 are in front of the plate 65, the folded forms are so inserted that the 95 stubs 66 lie between the under, or red, belt and the plate 65; the main portion 74 of the form being forward of the outer or black belt. The black belt then prints only on the uncarbonized face of the red belt, and the red belt prints on the stub, and also, when desired, on the tally-sheet, presently 100 to be described.

The stubs, set together on the belt in a continuous chain, as above described, are 105 fed downward around the platen, and upward along and over the paper-shelf 48. This feed, as heretofore mentioned, is effected by reverse movement of the platen by the hand-wheel 13, bringing one after another of the forms to printing position. 110 The leading edge of the leading form having passed over the rear upper edge of the paper-shelf 48, has the bight thereof engaged by the pointed end 76 of a finger 77, secured by screws 78 to an arm 79, depending from and forming a continuation of the 115 right-hand frame-piece 40. The finger 77, as shown in Figure 3, is inclined outward, from front to rear, so that the point 76 thereof having been engaged in the bight 120 of the leading form, and the leading form continuing to be pushed rearward by the belt and succeeding forms, the finger 77 cams the leading form laterally to the right, and laterally across the face of its supporting carbon-belt, until the heavier or stub-carrying side of the form causes the form to fall laterally off of the carbon-belt. On being thus disconnected and in falling from 125 the carbon-belts, the forms may be guided 130

by the table 45 to a suitable receptacle. The table 45 has, however, the additional function of preventing the discharged form from fouling on the mechanism at the rear 5 of or under the paper-shelf 48.

A tally-sheet may be used in connection with the printing of the individual forms to provide a condensed summary of the printings on the several forms. The tally-sheet mechanism, shown in the drawings, is that set forth and described in detail in United States Patent to F. A. Hart, No. 1,281,160, dated October 8, 1918, to which reference is made for a detailed description 10 thereof. Briefly, this mechanism comprises a frame having side plates 80, through which pass rods 24 and 25, carried by brackets 17, secured to the plates 12, to serve as a support therefor. The side plates 80 are suitably fixed, with respect to each other, by collars on the shaft 25. Revolvable on the shaft 24 is a roll 81, from which a continuous tally-sheet 82 and a superposed carbon-strip 83 are fed, down behind and 20 around the platen, to a take-up roll 84. For turning the roll 84 to feed the tally-sheet and superposed carbon, there is a fast there-to a pinion 85, meshing with a pinion 86, keyed to the shaft 25. The shaft 25 is journaled for rotation in the brackets 26. Fast to the shaft 25 is a line-space-wheel 87, and mounted to swing freely on the shaft is an arm 88, carrying a pawl 89 for moving the ratchet-wheel 87; a spring, 30 not shown, holding the pawl against the ratchet-wheel. A link 90 connects the arm 88 to the line-space-slide 16. When, therefore, the carriage is returned by means of the line-space-lever, a line-space-movement of the shaft 25, and, 40 with it, the pick-up roll 84, is effected. No line-space-feed of the platen is, however, effected at such times, because, as hereinbefore stated, the line-space ratchet-wheel 14 is not operatively connected to the platen-axle 11. The tally-sheet 82, therefore, has feed in the usual direction, that is to say, in a direction opposite to the direction of feed of the individual forms 74 and carbon-belts 49 and 50. It will be noted that the 50 pressure-feed-rolls 51 lie outside the margins of the tally-sheet 82, so that the latter may move freely with reference to the platen.

In order that the pick-up roll or reel 84 may be turned, when desired, independently of its line-space mechanism, the gear 86 is shiftable longitudinally on the shaft 25. Normally, a coil spring 86^a, bearing at one 60 end against a collar 91, fixed on the shaft 25, and bearing at its other end against the hub 92 of the pinion 86, holds the latter in mesh with the gear 85; and, when free to do so, moves the gear 86 into mesh with the pinion 85. Supported by the tally-frame-

plates 80, and shiftable longitudinally therein, is a shaft 93, which bears at one end against the pinion 86 and at its other end carries a button 94. Pivotally mounted on the shaft 24 is a cam-plate 95, against which the button 94 is held by the action of the spring 86^a. This cam-plate carries a finger-piece 96, by means of which it may be rotated on the shaft 24; and the cam-plate is so shaped that, upon rotation, it acts upon the button 94 to force the shaft 93 and pinion 86 to the left, thereby disengaging the latter from the pinion 85. Movement of the finger-piece 96 in the other direction permits the pinion 86 to be returned to mesh with the pinion 85. Suitable means (not shown) is provided for holding the cam-plate 95 in a position in which the pinions 85 and 86 are disengaged from one another, so that the tally-sheet and superposed carbon may be moved any desired distance without reference to the line-space mechanism therefor. To prevent over-run of the tally-sheet supply-roll 81, and to prevent slack in the tally-sheet and superposed carbon, there is shown in the Hart patent, above referred to, a spring-tension device, consisting of certain features not shown in the present drawings, to wit, a pinion connected to the reel 81 and meshing with another pinion on the shaft 97, which latter pinion has connected thereto a coil spring, urging the same in such direction as to hold the tally-roll taut; a slip connection being provided between such spring and the tally-roll, to permit of the necessary rotation of the latter by its line-space mechanism.

As shown in Figure 1 of the drawings, printing may be effected on the tally-sheet within and outside of the boundaries of the carbon-sheets 49 and 50 and stub 66. The carbon 83, superposed upon the tally-sheet, provides for printing on the latter, either within or without the boundaries of the form-stub 66. For printing within the boundaries of the form-stub 66, the carbon-belt 83 might be eliminated and the carbon-belt 50 used in lieu thereof; or, for printing on the tally-sheet outside of the boundaries of the stub 66, a wider belt 50 might be used. Where both of the carbon-belts 50 and 83 used, the belt 50 prints futilely on the uncarbonized back of the belt 83 within the field of the stub 66.

From the foregoing, it will be seen that individual forms may be rapidly fed, bottom end first, in a continuous chain, downward from the front of the platen, and that the writings on such forms may be condensed upon a tally-sheet fed in the reverse direction: the feed of the platen with the individual forms being effected by hand-rotation of the platen, and the feed of the tally-sheet being effected by the usual line-space mechanism operated in the act of returning

the carriage after the writing on each form.

Variations may be resorted to within the scope of the invention, and portions of the 5 improvements may be used without others.

Having thus described my invention, I claim:

1. In a typewriting machine for typing upon a succession of folded individual 10 form-sheets, a rotary platen, a carriage therefor, an endless carbon-belt passing around the platen and arranged to be driven thereby, a pulley on the carriage for holding the belt to the platen, and means for 15 turning the platen to cause the belt to be fed downward around the same from the front thereof; the belt being held clear of the carriage mechanism above the platen to permit the same to be interleaved with the 20 folded individual form-sheets, placed laterally thereover.

2. In a typewriting machine for typing upon a succession of folded individual form-sheets, a rotary platen, a carriage 25 therefor, a carbon-belt passing over the platen, a pulley on the carriage for holding the belt to the platen, means for turning the platen to cause the belt to be fed downward around the same from the front thereof, and 30 a gage strip paralleling the belt at one side thereof above the platen to serve as an aligning piece for the bights of the folded individual form-sheets passed laterally over the belt, at said strip, to embrace the belt.

3. In a typewriting machine for typing upon a succession of folded individual form-sheets, a rotary platen, a carriage therefor, a carbon-belt passing over the platen, a pulley on the carriage for holding 40 the belt to the platen, means for turning the platen to cause the belt to be fed downward around the same from the front thereof, and a belt-protecting and form-gaging strip paralleling the belt at one side thereof 45 above the platen to serve as an aligning piece for the bights of the folded individual form-sheets passed laterally over the belt, at said strip, to embrace the belt, said strip terminating above the platen to permit the 50 sheets to clear the same upon engagement with the platen.

4. In a typewriting machine for typing upon a succession of folded individual form-sheets, a rotary platen, a carriage 55 therefor, a carbon-belt passing over the platen, a pulley on the carriage for holding the belt to the platen, means for turning the platen to cause the belt to be fed downward around the same from the front thereof, a strip paralleling the belt at one side thereof above the platen to serve as an aligning piece for the bights of the folded individual form-sheets passed laterally over the belt, at said strip, to embrace the belt, said 60 strip terminating above the platen to permit

the sheets to clear the same upon engagement with the platen, and pressure-feed-rolls for gripping the sheets to the platen before they have cleared the aligning strip.

5. In a typewriting machine, a rotary 70 platen, a carriage therefor, a plurality of superposed carbon-belts passing over the platen, pulleys on the carriage for holding the belts to the platen, means for turning the platen to cause the belts to be fed downward around the same from the front thereof, and a work-sheet insertion guide interposed between the belts above the platen to 75 guide a work-sheet ply laterally into position between the belts.

6. In a typewriting machine, a rotary platen, a carriage therefor, a plurality of superposed carbon-belts passing over the platen, pulleys on the carriage for holding the belts to the platen, means for turning the platen to cause the belts to be fed downward around the same from the front thereof, and a work-sheet insertion guide interposed between the belts above the platen to 85 guide a work-sheet ply laterally into position between the belts, the belt to the rear of the guide being shiftable at will to the front of the guide for insertion of the work-sheet ply behind the same.

7. In a typewriting machine, a rotary 90 platen, a carriage therefor, a plurality of superposed carbon-belts passing over the platen, pulleys on the carriage for holding the belts to the platen, means for turning the platen to cause the belts to be fed downward around the same from the front thereof, a work-sheet insertion guide interposed between the belts above the platen to guide a work-sheet ply laterally into position between the belts, and idlers at the rear of the 95 guide for holding the rear belt clear of the 100 guide.

8. In a typewriting machine, a rotary platen, a carriage therefor, a plurality of superposed carbon-belts of different colors 110 passing over the platen, pulleys on the carriage for holding the belts to the platen, means for turning the platen to cause the belts to be fed downward around the same from the front thereof, and a work-sheet insertion guide interposed between the belts above the platen to guide a work-sheet ply laterally into position between the belts, the belt to the rear of the guide being shiftable at will to the front of the guide for insertion 115 of the work-sheet ply behind the same.

9. In a typewriting machine, a rotary platen, a carriage therefor, a carbon-belt passing over the platen, a pulley on the carriage for holding the belt to the platen, means for turning the platen to cause the belt to be fed downward around the same from the front thereof, a paper-shelf for 120 guiding the belt, with work-pieces thereon, rearward of the platen, and a chute for the 125 130

- work-pieces connected to the rear end of the paper-shelf.
10. In a typewriting machine, a rotary platen, a carriage therefor, a carbon-belt passing over the platen, a pulley on the carriage for holding the belt to the platen, means for turning the platen to cause the belt to be fed downward around the same from the front thereof, a paper-shelf for guiding the belt, with work-pieces thereon, rearward of the platen, a chute for the work-pieces connected to the rear end of the paper-shelf, and means for disengaging the work-pieces from the belt and delivering the same to the chute.
11. In a typewriting machine, a rotary platen, a carriage therefor, a carbon-belt passing over the platen, a pulley on the carriage for holding the belt to the platen, means for turning the platen to cause the belt to be fed downward around the same from the front thereof, and means at the rear of the platen for engaging the bights of work-pieces folded laterally over the belt, to disengage such work-pieces from the belt.
12. In a typewriting machine, a rotary platen, a carriage therefor, a carbon-belt passing over the platen, a pulley on the carriage for holding the belt to the platen, means for turning the platen to cause the belt to be fed downward around the same from the front thereof, and a finger at the rear of the platen, inclined rearward and laterally outward from one margin of the belt, to engage in the bights of work-pieces folded over the belt, and, by the feed of the belt, to cause such work-pieces to be drawn, by their bights, laterally of the belt until the work-pieces drop from the belt.
13. In a typewriting machine, a rotary platen, a carriage therefor, a paper-shelf on the carriage at the rear of the platen, a frame secured upon the front of the carriage and resting upon the paper-shelf, a pulley on said frame above the platen, a second pulley on the frame to the rear of the paper-shelf, and an endless carbon-belt carried by the platen and the pulleys.
14. In a typewriting machine, a rotary platen, means for holding a tally-sheet against the platen, means for effecting a feed of work-sheets down to and around the platen from the front thereof independently of the tally-sheet, and means for effecting a feed of the tally-sheet in the opposite direction independently of the work-sheets.
15. In a typewriting machine, a rotary platen, line-space mechanism therefor, means for holding a tally-sheet against the platen, means for effecting a feed of work-sheets down to and around the platen from the front thereof independently of the tally-sheet, by movement of the platen independently of the line-space mechanism, and means for effecting a feed of the tally-sheet 65 in the opposite direction, independently of the work-sheets, by actuation of the line-space mechanism.
16. In a typewriting machine, a rotary platen, line-space mechanism therefor, a carriage for the platen, means for holding a tally-sheet against the platen, means for effecting a feed of work-sheets down and around the platen from the front thereof independently of the tally-sheet and outside 70 of the tally sheet, by movement of the platen independently of the line-space mechanism, and a carriage-return device for effecting a feed of the tally-sheet in the opposite direction, independently of the work-sheets, by 75 actuation of the line-space mechanism.
17. In a typewriting machine, a rotary platen, line-space mechanism therefor, means for holding a tally-sheet against the platen, pressure-rolls on the platen outside of the tally-sheet margin positions for effecting a feed of work-sheets down and around the platen from the front thereof independently of the tally-sheet and outside of the tally-sheet, by movement of the platen independently of the line-space mechanism, and means for effecting a feed of the tally-sheet in the opposite direction, independently of the work-sheets, by actuation of the line-space mechanism.
18. In a typewriting machine, a rotary platen, means for holding a tally-sheet against the platen, means for effecting a feed of work-sheets down to and around the platen from the front thereof independently of the tally-sheet including a carbon-belt on which the work-sheets are carried, and means for effecting a feed of the tally-sheet in the opposite direction independently of the work-sheets, so that entries made on successive work-sheets will be caused to appear on the tally-sheet in the order in which the work-sheets were typed.
19. In a typewriting machine, a rotary platen, means for holding a tally-sheet against the platen, means for effecting a feed of folded work-sheets down to and around the platen from the front thereof independently of the tally-sheet including a carbon-belt on which the work-sheets are carried, a lateral guard and gage around which the folded work-sheets may be placed with one ply thereof between the carbon-belt and the tally-sheet, and means for effecting a feed of the tally-sheet in the opposite direction independently of the work-sheets.
20. In a typewriting machine, a rotary platen, means for holding a tally-sheet against the platen, pressure-rolls on the platen outside of the tally-sheet margin positions for effecting a feed of work-sheets down and around the platen from the front

- thereof independently of the tally-sheet, means for effecting a feed of the tally-sheet in the opposite direction independently of the work-sheets, a carbon-belt on which the 5 work-sheets are carried, and a lateral guard and gage, in alignment with one of the pressure-rolls, around which the work-sheets may be folded with one ply thereof between the carbon-belt and the tally-sheet.
- 10 21. A method of feeding individual form-sheets through a typewriting machine, consisting in folding one form laterally around a belt; similarly folding the next form around the belt above the first form and in 15 underlapping relation thereto; and moving the belt downward and around the platen to bring form after form first to printing position and then around under the platen to the rear thereof.
- 20 22. A method of feeding individual form-sheets through a typewriting machine, consisting in folding one form laterally around a belt; similarly folding the next form around the belt above the first form 25 and in underlapping relation thereto; moving the belt downward and around the platen to bring form after form first to printing position and then around under the platen to the rear thereof; and interposing 30 a finger at a laterally outward incline in the bight of the leading typed form, to cause such form to be cammed off of the belt by the movement of the latter.
23. A method of preparing and feeding 35 individual form-sheets through a typewriting machine, consisting in cutting the sheets at one edge thereof; folding the sheets on the line of the cut; placing the first sheet on a belt with one ply thereof on each side 40 of the belt; similarly placing the next sheet on the belt above the other, the edges of one of the sheets being set in the cut in the other to be interlocked therewith; and moving the belt downward and around the platen to 45 bring form after form first to printing position and then around the platen to the rear thereof.
24. A method of feeding individual form-sheets through a typewriting machine, consisting in folding one form laterally around a belt; similarly folding the next form around the belt above the first form with the lower edge of the last sheet under the upper edge of the preceding sheet, and guarded by a cut therein along the fold; and moving the belt downward and around the platen to bring form after form first to printing position and then around under the platen to the rear thereof. 50
25. In a typewriting machine for writing upon a succession of individual forms, the combination with a revoluble platen, of a conveyor belt passing around the platen and having a frictional face to engage the forms and conduct them to the platen, a side gage 55 for squaring the forms with relation to the platen as they are placed against the belt by the operator, and means to bear against the forms to press them into frictional contact with the belt as they travel toward the 60 platen, to prevent their slipping relatively to the belt and so to assure their being maintained in the squared condition determined by the gage. 65
26. In a typewriting machine for typing 70 upon a succession of folded individual forms, a rotary platen, a carbon belt to pass with the folded forms around the platen for making impressions upon the inner plies thereof, the arrangement being such that the 75 folded forms can be placed upon the belt to enfold it, and a guard constructed and arranged to prevent a clumsy operator from moving his hand against the carbon belt in placing a folded form upon it, to protect 80 the carbon belt against mutilation. 85
